United States Patent Office

Des. 188,444
Patented July 19, 1960

188,444

AIR CUSHION VEHICLE

Melville W. Beardsley, Severna Park, Md., assignor to
National Research Associates, Inc., Laurel, Md., a cor-
poration of Maryland

Filed May 2, 1960, Ser. No. 60,421

Term of patent 14 years

(Cl. D71—1)

FIG. 1.

FIG. 2.

FIG. 3.

FIG. 4.

FIG. 5.

Fig. 1 is a top plan view of an air cushion vehicle showing my new design;

Fig. 2 is a side elevational view thereof;

Fig. 3 is a rear elevational view thereof;

Fig. 4 is a front elevational view thereof; and

Fig. 5 is a perspective view of an air cushion vehicle.

What is claimed is:

The ornamental design for an air cushion vehicle, as shown.
